UNITED STATES PATENT OFFICE.

WILLIAM O. SMITH, OF MEDFORD, MASSACHUSETTS.

DESIGN FOR A WIRE SCOOP.

SPECIFICATION forming part of Design No. 30,890, dated May 30, 1899.

Application filed April 10, 1899. Serial No. 712,555. Term of patent 7 years.

To all whom it may concern:

Be it known that I, WILLIAM O. SMITH, a citizen of the United States, residing at Medford, in the county of Middlesex and State of Massachusetts, have invented and produced a new and useful Design for a Wire Scoop, of which the following is a description, reference being had to the accompanying drawings, forming a part thereof.

10 Figure 1 of the drawings shows in side elevation a wire scoop, illustrating my design; and Fig. 2 is a front elevation thereof with one of the loops broken out.

15 The leading feature of my design for a wire scoop consists of two arms at one end merging into and united by a spiral, each arm terminating at its outer end in a closed loop, the loops being slightly curved or bent toward each other near their outer ends.

20 In the drawings the two straight arms a are united at one end by and merge into a

spiral or coil a' , forming a continuation of the arms, the outer end of each arm terminating in a closed loop a^2 , herein shown as rounded at their outer ends and with their sides converging as they join the arms a , the loops being opposed to each other and having their sides slightly curved outwardly, as at a^3 , that the loops are bent toward each other near their outer ends. 25

Having fully described my design, what I claim, and desire to secure by Letters Patent, is—

30 The design for a wire scoop, substantially as herein shown and described. 35

In testimony whereof I have signed my name to this specification in the presence of two subscribing witnesses.

WM. O. SMITH.
